UNITED STATES PATENT OFFICE.

ORVILLE JAY HIMES, OF OSWEGO, NEW YORK.

UMBRELLA.

1,310,481.

Specification of Letters Patent. Patented July 22, 1919.

Application filed February 8, 1917, Serial No. 147,442. Renewed November 13, 1918. Serial No. 262,401.

To all whom it may concern:

Be it known that I, ORVILLE JAY HIMES, a citizen of the United States, residing at Oswego, in the county of Oswego and State 5 of New York, have invented certain new and useful Improvements in Umbrellas, of which the following is a specification.

This invention relates to an improved folding umbrella and the principal object 10 of the invention is to provide an umbrella having an improved telescoping or sliding rivet construction and with improved means for connecting the ribs with the staff, an improved type of notch and slide being mounted 15 upon the staff and the staff being formed in sections having improved means for releasably holding the sections in an extended position when in use.

Another object of the invention is to so 20 construct this umbrella frame that the stretchers may be held substantially parallel to the staff when telescoping the ribs, spreaders being connected with the improved notch and engaging the cover so that the cover will 25 be moved outwardly when telescoping the ribs thus permitting the ribs to telescope without the cover interfering with the movement of the ribs.

This invention is illustrated in the accompanying drawings, wherein:—

Figure 1 is a view in elevation of the improved umbrella frame with some of the ribs removed for the sake of clearness.

Fig. 2 is a fragmentary view of the umbrella frame in the folded position, the view being partially in elevation and partially in section,

Fig. 3 is a fragmentary sectional view taken along the line 3—3 of Fig. 1,

Fig. 4 is a fragmentary view of the frame in the folded position shown partially in elevation and partially in section,

Fig. 5 is a fragmentary perspective view of the slide.

Fig. 6 is a fragmentary view in elevation of one of the ribs,

Fig. 7 is a view in plan of that portion of the rib shown in Fig. 6,

Fig. 8 is a fragmentary view in elevation 50 showing the staff folded,

Fig. 9 is a view similar to Fig. 8 showing the inner joint of the staff folded,

Fig. 10 is a fragmentary sectional view through the handle section shown in Fig. 8,

Fig. 11 is a sectional view taken at right angles to the view shown in Fig. 10,

Fig. 12 is a fragmentary sectional view taken along the line 12—12 of Fig. 10,

Fig. 13 is a fragmentary view in elevation of the inner staff joint, and,

Fig. 14 is a transverse sectional view taken along the line 14—14 of Fig. 13,

Fig. 15 is a fragmentary view showing the staff and notch in elevation.

The staff of this umbrella is formed in 65 sections 15, 16 and 17, the handle section carrying the handle 18, and a core 19 is slidably mounted in the section 16 and provided at its inner end with a tongue 20 having a socket formed therein. The outer end of the 70 core is connected with a coupling block 21 sliding in the section 16 and limited in its outward sliding movement by a pin 22 positioned in a slot 23 formed in the staff section 16 as shown in Fig. 13. This coupling 75 21 is connected with the reduced end portion 24 of the staff section 16 by a link 25, the reduced end portion 24 of the section 15 being of proper size to fit into the section 16 when the staff is straightened 80 and the section 16 moved toward the section 15. It should be noted that the section 15 is cut to provide an inclined abutment shoulder 26 conforming in contour to the end of the section 16 as shown in Fig. 9 thus providing 85 a lock which will prevent rotary movement of the two sections when the staff is in the extended position shown in Fig. 1.

In the opposite end portion of the section 16 there is provided a slot 27 through which 90 extends the bill 28 and standard or pivot 29 of the latch 30. This latch is carried by the coupling or block 31 and from an inspection of Figs. 10 and 11, it will be readily seen that when the section 16 is moved to extend 95 upon the reduced end of the section 15, and the link 32, block 31 and section 17 move into the section 16 as far as permitted by the bill of latch 30. The bill of this latch will pass into the socket 20 thus locking the pawl 100 against longitudinal movement in the section 16. Therefore the single latch 30 may serve to releasably hold the section 17 and the section 16 against movement when in the extended position for use. It should be further noted that the section 17 is provided 105 with an abutment shoulder 33 which will operate with the inclined cut end of the sec-

tion 16 to prevent rotary movement of the two sections. This removes strain from the latch and prevents slipping.

The notch 34 is provided with a sleeve 35 slidably mounted upon the section 15 of the staff and provided with a longitudinally extending slot 36 in which is positioned the pin 37 for limiting the sliding movement of the sleeve upon the staff. A cup 38 is mounted upon the sleeve 35 above a sliding notch 34 and incloses the base and cam plate 39 slidably mounted upon the sleeve 35 below the notch 34. This cam plate is provided with a neck 40 and in order to move the cam plate longitudinally upon the sleeve 35, there is provided a sliding plate 41 having lower and upper flanges or lugs 41', the lugs extending above the notch 34 and below the neck 40 of the cam as shown in Fig. 15. This slide is mounted in a slot formed in the sleeve 35 and as the sleeve moves longitudinally upon the staff, the slide will be engaged by the sleeve and moved to bring the cam plate into engagement with the cam fingers 42 of spreaders 43. These spreaders are connected with the notch and are connected with the umbrella cover so that the cover may be moved out of the way when telescoping the ribs to be hereinafter described.

30 The slide 44 is slidably mounted upon the staff and carries a cup or collar 45 upon which there is mounted a ring 46 moved to the position shown in Fig. 4 when it is desired to telescope the ribs. These ribs are provided with inner sections 47 pivotally connected with the notch and outer sections 48 slidably connected with the inner sections by means of bearings 49 and 50. The bearings 49 which form hinge brackets for connecting the stretchers 51 with the ribs are carried by the inner ends of the outer sections and have sleeves 49' through which the inner sections pass and the bearings 50 are carried by the outer ends of the inner sections and are provided with tongues bent to provide eyes 50' through which the outer sections 48 pass. It should be noted that the tongues 50' engage the hinge brackets or bearings 49 thus forming abutments limiting the outward movement of the outer rib sections. Springs 52 are carried by the slide 44 and slidably engage the stretchers 51 as shown in Fig. 5 and not only serve to assist in the initial opening of the umbrella but also serve to resist opening of the umbrella beyond a desired amount. This will prevent the umbrella from being turned inside out by strong winds.

With the umbrella open, as shown in Fig. 60 1, it can be closed in the ordinary manner and unless it is desired to fold the umbrella, it will when closed resemble an ordinary umbrella. If it is desired to close the umbrella, the ring 46 will be moved onto the stretchers 51 to the position shown in Fig. 4

and will serve to hold the stretchers parallel to the staff and prevent opening of the umbrella when the slide is moved toward the notch. As this slide is moved toward the notch, the hinge bearings will be moved toward the notch thus carrying the outer rib sections inwardly along the sides of the inner rib sections. At the same time, the spreaders 43 will be moved outwardly through the action of the cam plates as previously described thus spreading the cover and making room for the ribs and the outer portion of the cover. Further movement of the slide toward the notch will serve to force the notch up into the cup 38 and will draw the staff to the position shown in Fig. 2. The latch 30 can now be swung to release the core 19 and the three sections of the staff can be drawn apart and folded as shown in Figs. 9 and 10. It will thus be seen that with this structure, the umbrella can be folded into a compact mass and can be put into a small space. When it is desired to again use the umbrella, it is simply necessary to straighten the staff and connect the sections thereof as previously described and then draw the slide 44 toward the handle 18. This will draw the outer rib sections outwardly and return the notch to the position shown in Fig. 1. The ring 46 can then be returned to its position upon the collar 45 and upon again moving the slide toward the notch, the ribs will be swung outwardly to a raised position. A collapsible umbrella has thus been provided having a very efficient structure.

What I claim is:—

1. An umbrella comprising a staff, a cup provided with a sleeve slidably mounted upon the staff, a notch slidably mounted upon the sleeve of said cup, a cam plate slidably mounted upon the sleeve, ribs having inner sections pivotally connected with the notch and outer sections slidably connected with the inner sections, spreaders pivotally connected with the notch and extending in operative relation to the inner sections of the ribs for engaging a cover, cam lugs extending from the spreaders for engagement by the cam plate to move the spreaders outwardly, a slide mounted upon the staff, and stretchers pivotally connected with the slide and with the inner end portions of the outer sections of said ribs.

2. An umbrella comprising a staff, a cup provided with a sleeve slidably mounted upon the staff and limited in its sliding movement, a notch slidably mounted upon the sleeve, ribs having slidably connected inner and outer sections, the inner sections being pivotally connected with the notch, a slide mounted upon the staff, and stretchers pivotally connected with the slide and outer sections of the ribs for moving the outer sections of the ribs longitudinally of the inner

sections when the stretchers are held parallel to the staff, the inner end portions of the ribs and said notch moving into said cup and said cup moving toward the end of said staff
 5 when the stretchers are substantially parallel to the staff and the slide moves toward said notch.

3. An umbrella comprising a staff, a notch, a slide, ribs pivotally connected with the
 10 notch, spreaders pivotally connected with the notch and provided with cam lugs, a plate for engagement with the cam lugs for moving the spreaders outwardly when the cam lugs and plate are in engagement, and
 15 stretchers pivotally connected with the slide and ribs.

4. An umbrella comprising a staff, a notch, ribs having inner and outer sections, the inner sections being pivotally connected
 20 with the notch and the outer sections slidably connected with the inner sections, a slide, stretchers pivotally connected with the slide and with the inner end portions of the outer sections of said ribs, and a ring carried
 25 by said slide and movable upon the stretchers for releasably holding the stretchers substantially parallel to the staff when moving the outer sections of the ribs longitudinally of the inner sections of the ribs.

30 5. An umbrella comprising a staff, a notch

carried by the staff, ribs pivotally connected with the notch, a slide mounted upon the staff, stretchers pivotally connected with the ribs and with the slide, and springs connected with the slide and slidably connected 35 with the stretchers for giving the umbrella initial movement toward an open position and resisting opening of the umbrella beyond a desired amount.

6. An umbrella comprising a staff, a notch 40 carried by the staff, ribs including inner sections pivotally connected with the staff, outer sections, a hinge bracket rigidly mounted upon the inner end portion of the outer section of a rib and slidably engaging the inner section of the rib, a bearing bracket rigidly mounted upon the outer end portion of the inner section of a rib and slidably engaging the outer section thereof and engaging the hinge bracket to limit the sliding 45 movement of the sections, a slide mounted upon the staff, and stretchers pivotally connected with the slide and pivotally connected with the hinge brackets of said ribs.

In testimony whereof I affix my signature 55 in presence of two witnesses.

ORVILLE JAY HIMES.
